UNITED STATES PATENT OFFICE.

ISAAC FRANCIS TAYLOR, OF EAST DULWICH, LONDON, AND SAMUEL PICK, OF LONDON,
ENGLAND.

SHIP'S-BOAT STORING, LOWERING, AND RAISING APPARATUS.

1,133,826.

Specification of Letters Patent.

Patented Mar. 30, 1915.

Application filed June 7, 1913. Serial No. 772,322.

To all whom it may concern:

Be it known that we, ISAAC FRANCIS TAYLOR and SAMUEL PICK, subjects of the King of Great Britain and Ireland, residing at 5 Upland road, East Dulwich, London, S. E., England, and 117 Queen Victoria street, London, E. C., England, respectively, have invented certain new and useful Improvements in Ships'-Boat Storing, Lowering, and Raising Apparatus, of which the following is a specification.

This invention has for its object to enable boats to be stored and to be launched quickly and safely from store from either side of a ship and to enable a number of boats to be loaded with passengers before being carried outward and lowered.

According to this invention carriers such as chains or wire ropes are mounted to run 20 on tracks or supports arranged athwart the boat deck, and above the carriers is a platform supporting the raising and lowering gear which comprises pivoted cantalivers or davits adapted to swing out to throw the 25 boats clear of the ship's sides and carrying pulleys over which the falls pass to a winch barrel provided with a brake arranged to act on the drum of the winch to control the lowering of the boats.

Between the carriers which are spaced apart a suitable distance the boats are arranged to be suspended by attachment at the stern and stem, and when outboard are disengaged from the carriers and engaged 35 with the falls. When stored the boats are supported on the boat deck below the carriers on chocks which are lowered when the boats are ready to be run outboard so as to be out of the way of the keels of the boats.

In the accompanying drawings, Figures 1 and 2 are elevations at right angles of boat storing, lowering and raising apparatus constructed according to this invention. Fig. 3 is a sectional plan showing the chocks, 45 Figs. 4 and 5 are end and side elevations of the boats. Fig. 6 is an elevation partly in section of a modified construction of an apparatus, and Fig. 7 is an elevation at right angles to Fig. 6.

As shown in Figs. 1 to 5 a framing is 50 erected on the boat deck *a* consisting of stanchions *b* supporting bearers or beams *b'* *b''* at their upper ends for the platform and chain tracks *c* fixed to the stanchions at a suitable height on which endless chains *d* 55 are supported. Each chain track is formed of a pair of plates *c' c''* having flanges *c''* at their lower ends upon which rollers *d'* upon the endless chains *d* are arranged to run, eyes *d''* attached to the chains being arranged to hang between the flanges. The chains run between the track plates *c' c''* and over sprocket wheels *e* mounted at opposite ends of the track, one or both pairs of sprockets being connected by shafts such as 60 *f* adapted to be operated through worm gearing *g*, spindle *h* and hand wheel *i* from the platform or by a crank handle applied to the end of the shaft at *f'*. Near the ends of the boats suspending hooks *j* are pivot- 70 ally mounted which are adapted to be engaged with the eyes *d''* on the chains. These suspending hooks *j* are pivoted at the stern and stern between cheek plates *j'* provided with a pair of upwardly projecting fingers 75 or prongs *j''* arranged to disengage the eye of the falls when the hook drops by its own weight on the load being taken off when the boat is water-borne. Two or three hooks may be carried on the same shank, one indicated by the reference 1, serving to connect with the carrier chains, another 2, with the falls for lowering the boat and another 3 in cases where the falls are attached to raise 80 the boat on board. In the latter case the hook 3 has a spring closing tongue *3''* to prevent accidental release of the rope.

Several boats can be stored below the chains *d* which extend from side to side of the ship, or as far as space will permit, and other boats are brought into position by means of a trolley *k* or the like moving on a track *k'* which extends along the boat deck to the carrier. This trolley is prevented from leaving the rails by brackets *k''* which project from the frame of the trolley under the rails as shown in Fig. 1. The falls *l* on the same side of the ship run over pulleys *m*

on the outer ends of pivoted cantalivers or davits n and over other pulleys m to the same winch barrel m^2 mounted on the platform above the beams b^2 . The barrel has a flange at its middle which separates the falls from different davits when being wound on the winch barrel. On one end of the winch barrel a brake drum o is provided and is acted upon by a brake band o' and lever o^2 10 to control the lowering of the boat. Suitable means are provided to disengage the falls when the boat is water-borne, after which the falls are raised by rotating the winch drums. Suitable motive power may 15 be employed to operate the winch when it is desired to raise a boat.

Each cantaliver or davit n comprises pairs of spaced or bifurcated arms n' n^2 connected together by brace bars n^3 and pivoted at 20 n^4 to a suitable base n^6 fixed to the beams b' . A link or stay p also pivoted to the base n^6 passes over the inner arms n' and limits the outward movement of the cantaliver. In their outboard positions the cantalivers are 25 locked by catches q which engage under the beams b' of the framing. When the falls are wound up by rotating the winch drums the catches q are released by weights or balls 30 q' on the falls l just before said balls engage the undersides of the cantalivers. By the further upward movement of the weights the cantalivers are caused to swing inboard about their pivots n^4 . During this movement the balls seat themselves in hook 35 shaped projections n^5 on the outer arm n^2 of the cantaliver, so that on a boat being subsequently connected to the falls the weight first acts through the balls and hooks n^5 to pull the davits outboard. In some cases the 40 outer arms of the davits diverge below the projections n^5 to the pivots n^4 , to leave a free space between them so that should it be desired to raise goods or mail packages by the davits such goods can be swung 45 through the davits and delivered into a chute in the deck.

As clearly illustrated in Figs. 1 and 3 the chocks are formed of transverse beams s suitably recessed at s' to receive the keels of 50 the boats and spaced apart to engage the boats near the bow and stern. Pivoted depending links t connect the chock beams s with a series of angle levers u mounted to 55 oscillate in a vertical plane on suitable brackets v fixed to the deck, the levers u of each beam being connected with a common rod u' extending along the underside of the beam, the rods u' being themselves connected by bell crank levers u^2 and rodging u^3 60 with screw gear u^4 actuated by a spindle u^5 and hand wheel w . Vertical guides x extend upward between guide rolls x' on the chock beams to prevent longitudinal movement of the beams which are maintained

parallel with the deck during their upward 65 and downward movement.

It will be readily understood that in some cases the apparatus may be constructed to carry two or more rows of boats one above the other or at the same level. A construction is illustrated in Figs. 6 and 7 for carrying two rows of boats. In this construction the endless carrier chains d run alongside grooved tracks c^3 over which run rollers d' mounted loosely on spindles d^3 which pivot in the links of the chains. Bars r extend between the two carrier chains d and are provided with eyes d^2 for the suspension of the boats. These bars are fixed to or formed integral with the spindles d^3 of the rollers 75 so that the bars can turn freely about their longitudinal axes to enable the boat suspending eyes d^2 to hang vertically when passing around the ends of the guide tracks. For actuating the endless carrier chain in 85 this case spur gear wheels e' are fixed to the axles of the sprocket wheels e and gear with spur wheels e^2 on the shaft f^2 which is actuated through worm gearing g h and hand wheel i , or by a crank handle applied to the 90 end of the shaft in the same manner as the shaft f hereinbefore described. Chocks s are provided for the upper row of boats and operated in like manner to the chocks already described, the hand wheel w and screw 95 gear actuating the lower chocks being also connected with the upper chocks by a connecting rod and suitable levers.

What we claim and desire to secure by Letters Patent is:—

1. In an apparatus for storing, lowering and raising ships' boats, the combination of 100 endless carriers disposed transversely of the ship; tracks for said carriers and extending from side to side of the ship; boat lowering and raising gear coöoperating with the carriers; a series of chocks for supporting the boats in position under the carriers; said boat lowering and raising gear comprising davits adapted to swing outboard in 110 vertical planes to throw the boats clear of the ship's sides; falls on said davits; and means for locking the davits in outboard position and adapted to be released by the winding up of the falls.

2. In an apparatus for storing, lowering and raising ships' boats, the combination of 115 endless carriers disposed athwart the ship; davits associated with the carriers adapted for swinging the boats outboard in a vertical 120 plane; falls hanging from said davits and carrying weights thereon; and a seating provided on the davit for receiving the weights.

3. In an apparatus for storing, lowering and raising ships' boats, the combination of 125 endless carriers disposed athwart the ship; davits associated with the carriers adapted for swinging the boats outboard in a verti-

cal plane; falls hanging from said davits and carrying weights thereon; a seating provided on the davit for receiving the weights; pulleys on the davits; a winch for controlling the falls; a brake for controlling the winch; and ropes passing over the pulleys from the boats to the winch.

In testimony whereof we have affixed our signatures, in presence of two witnesses.

ISAAC FRANCIS TAYLOR.

SAMUEL PICK.
